UNITED STATES PATENT OFFICE.

GEORGE T. PEARSONS, OF NEW YORK, N. Y.

FIRE-EXTINGUISHER.

1,214,581.

Specification of Letters Patent. Patented Feb. 6, 1917.

Application filed May 5, 1916. Serial No. 95,523.

To all whom it may concern:

Be it known that I, GEORGE T. PEARSONS, a citizen of the United States, residing in the borough of Manhattan, in the city, county, and State of New York, have invented new and useful Improvements in Fire-Extinguishers, of which the following is a specification.

This invention relates to fire extinguishers in which a fire extinguishing liquid, such as carbon tetrachlorid, is discharged from a reservoir by an expelling agent or gas generated in the reservoir, the production of such gas being the reaction between suitable materials, such as bicarbonate of soda and sulfuric or hydrochloric acid, normally maintained in a separated condition within the reservoir, and one of said materials, preferably the acid, being contained in a fragile receptacle which may be readily ruptured or broken, and when it is desired to utilize the extinguisher such receptacle is broken causing the gas generating materials to mix and generate gas and the expansive force of such gas expelling the liquid from the reservoir; and it is the primary object of the present invention to simplify and improve the general construction of extinguishers of this character to thereby cheapen the cost of manufacture and increase the efficiency thereof.

A further object of the invention is to provide improved means to hold the gas generating materials in a separated condition in the reservoir and such materials with the reacting mixture free from the liquid in the tank.

A further object of the invention is to provide improved means to support the acid carrier and to rupture or break said carrier to cause it to mix with the other gas generating material.

In extinguishers of this type the fire extinguishing liquid is of such a nature that it will not injure or mar articles, such as wearing apparel, furniture and draperies, or corrode metal, with which it may come in contact, while the materials the reaction of the mixing of which constitutes the expelling agent are of such a nature that they will injure and ruin such articles as wearing apparel, furniture or draperies

and quickly corrode metallic parts with which they may come in contact. It very often happens that a part of said gas generating materials is carried off with the generated gas and expelled with the fire extinguishing liquid with the above deleterious results.

It is a further object of the invention to provide means to render the expelling agent or gas anhydrous or dry and non-acid before it is utilized to expel the fire extinguishing liquid.

Other objects and advantages will hereinafter appear.

In the drawing accompanying and forming a part of this specification, there is shown a cross sectional elevational view of a fire extinguisher illustrating an embodiment of my invention.

In the embodiment of my invention shown in the drawing a fire extinguishing liquid, such as carbon tetrachlorid, is contained in a reservoir or tank consisting of a body portion 2, preferably cylindrical in shape, closed at one end, as at 3, to constitute the bottom and constructed to form a supporting base for the extinguisher. In the upper end there is a head 4 having a central opening closed by a removable cover 5. Secured in an opening in the head communicating with the exterior of the reservoir is a discharge tube 6, the said tube extending to adjacent the bottom of the reservoir with such end closed by a check valve closing into and opening outward from the reservoir, as shown at 7. Communication to the exterior of the reservoir through said tube may be shut off by a valve 8 connected to the tube 6 by a fitting 9 and to which valve is connected the usual flexible nozzle tipped hose 10.

One of the gas generating materials, such as bicarbonate of soda, is carried in a receptacle 13 which has screw threaded connection, as at 12, with external screw threads on a depending annular flange 11 of the cover to removably connect the same thereto, and whereby the cover serves to close the upper end of the receptacle. The other gas generating material, such as sulfuric or hydrochloric acid, is carried in a fragile receptacle 14, such as a glass bottle.

This receptacle has a filler opening or neck which is adapted to have a suitable closure and seal, as shown at 15, a composition of glycerin and litharge having been found to 5 answer the purpose. The receptacle has a restricted bottom and an annular contracted and thinned portion adjacent the bottom which is substantially of V-shape in cross section, as shown at 16, for a purpose 10 to be hereinafter described. The receptacle 14 is carried suspended within the first receptacle 13 by a tubular member or receptacle 17 having screw threaded connection with internal screw threads on the depend- 15 ing flange 11 of the cover 5, as at 18, to removably connect the same thereto. The end of this member opposite to where it is connected to the cover flange, or the bottom 19, inclines downward from the walls to the 20 center as shown, and has a central perforation 20 and may have a plurality of additional perforations laterally of said central perforation. It will be noted that the receptacle 14 rests or is supported upon the 25 bottom 19 at or adjacent the lateral edges of the bottom only.

The agent or gas to expel the liquid from the reservoir is produced by the reaction of the mixing of the acid in the receptacle 30 14 with the bicarbonate of soda in the receptacle 13, and to free the acid from the receptacle 14 means are provided to rupture or break said receptacle. For this purpose there is provided a plunger 21 having a head 35 22 substantially of the same diameter as the receptacle 17, which head abuts against the bottle 14. A second plunger 23 passes through the cover and has screw threaded connection therewith, preferably of a steep 40 pitch, as at 24, and also passing through stuffing boxes 25 and 26, carried at the exterior and interior of the cover, the said plunger at the outer end having an operating handle or hand-grip 27 to operate the plunger 45 from the exterior of the reservoir. The inner end of said plunger co-operates with the plunger 21, as at 28, and as the plunger 23 is moved inward it will engage with said plunger 21 and force the head 22 against 50 the bottle exerting a pressure on the latter, and this pressure on the bottle by the engagement of the bottom of the bottle with the bottom 19 of the carrier for said bottle will cause the bottle to be broken or ruptured 55 at the annular thinned recessed portion 16, freeing the contents of the bottle, which will drip gradually through the openings 20 in the bottom of the bottle carrier 17 onto the material in the receptacle 13 imme- 60 diately generating gas. This gas passes up through the openings 20 and perforations 29 in the plunger head 22, and through an outlet or outlets 30 in the depending annular flange 11 of the cover leading into the

reservoir where the expansive force of said 65 gas exerted on the liquid therein will cause said liquid to unseat the valve 7 in the outlet tube 6 and forcibly eject the liquid through said tube and through the connected hose 10, it being understood of course that the 70 valve 8 is opened when the extinguisher is to be used. The outlets 30 are provided with spring influenced check valves 31 opening into and closing outward from the reservoir whereby the gas generating materials 75 and the reacting mixtures are maintained free from the liquid in the reservoir.

As stated the fire extinguishing liquid is of such a nature that it will not injure articles, such as wearing apparel, furniture, 80 draperies and the like, or corrode metal, with which it may come in contact, whereas the nature of the gas generating materials is such as to destroy and ruin any such articles and corrode metallic articles with 85 which it may come in contact, and it very often happens that parts of the gas generating materials are carried off with the generated gas into the reservoir and expelled with the fire extinguishing liquid with the 90 above deleterious results. To prevent this contingency means are provided to render the generated gas anhydrous or dry and non-acid by filtering the generated gas. For this purpose I provide a material through 95 which the generated gas passes to absorb any moisture in said gas, sodium carbonate having been found to answer the purpose. This absorbing material is located in the carrier 17 for the acid bottle above the plunger head 22, as shown at 32, the said head preventing this material from dropping into the reacting mixture, and the material is held in compact condition by a disk screen or perforated disk 33, this screen also preventing the generated gas from expelling any of the absorbing material through the outlets 30 and from choking said outlets. 100

From the foregoing and as shown in the drawing it will be noted that the parts carrying the gas generating materials and the gas filtering material, which is in the nature of a generator, are carried by the cover 5 and are removable from the reservoir with said cover, thus facilitating the removal of said parts for cleaning or otherwise, and for recharging. By locating the outlets 30 in the annular depending flange of the cover these outlets with the valves thereto may be readily examined and cleaned or others 120 substituted without disturbing the parts carrying the gas generating materials. 110

The reservoir may have an opening which may be in the nature of a filler opening normally closed by a threaded cap or plug 33. 125 This cap is also in the nature of a valve to let off the gas pressures from the reservoir should a fire be extinguished before all of

the contents of the reservoir have been expelled, and to prevent the expelling of the remainder of such contents in the reservoir. For this purpose the cap or plug has a port 5 34 extending axially thereinto and then extending laterally with the outlet in the side of the plug, which outlet is normally closed by the engagement of the plug or cap with the threaded wall of the opening. Should 10 it be desired to relieve the gas pressure in the reservoir it is only necessary to slightly unscrew the plug until the lateral outlet of the port communicates with the atmosphere. To facilitate the unscrewing of the cap it 15 may be constructed with a finger piece 35.

Having thus described my invention I claim:

1. In a fire extinguisher, the combination of a reservoir for a fire extinguishing liquid having a discharge outlet and an opening therein; a removable cover for said opening; a receptacle for a gas generating material carried by the cover suspended in the reservoir and with which the cover cooperates to provide a closed receptacle having an outlet leading into the reservoir; a second receptacle for a gas generating material in the first receptacle; a carrier for the latter receptacle; a plunger to abut 25 against said second receptacle; and a plunger passing through and having screw threaded connection with the cover with means to operate the same exterior of the reservoir to have movement into the carrier for the second receptacle and adapted to cooperate with the plunger abutting against the second receptacle to rupture the latter, substantially as and for the purpose specified.
2. In a fire extinguisher, the combination of a reservoir for a fire extinguishing liquid having a discharge outlet and an opening therein; a removable cover for said opening; a receptacle for a gas generating material carried by the cover suspended in the reservoir and with which the cover cooperates to provide a closed receptacle; a valved outlet from said receptacle leading into the reservoir; a receptacle of fragile 40 material for another gas generating material; a tubular carrier for said receptacle to carry said receptacle from the cover suspended in the first receptacle, and having an opening in the bottom to connect it with the first receptacle; and a plunger carried by the cover operable from the exterior thereof to rupture said fragile receptacle, substantially as and for the purpose specified.
3. In a fire extinguisher, the combination of a reservoir for a fire extinguishing liquid having a discharge outlet and an opening therein; a removable cover for said opening having a depending annular flange; a

receptacle for a gas generating material 65 connected to the depending flange of the cover to suspend said receptacle in the reservoir and with which the cover cooperates to provide a closed receptacle; valved outlets in the depending flange of the cover leading into the reservoir; a second receptacle connected to the depending flange of the cover to suspend said receptacle in the first receptacle with the bottom of said second receptacle at some distance above the bottom 70 of the first receptacle and having an opening in the bottom to connect the two receptacles; a fragile receptacle for a gas generating material carried by the second receptacle; a plunger normally abutting 75 against said fragile receptacle; and means passing through the cover operable from the exterior of the receptacle to cooperate with said plunger to rupture the fragile receptacle, substantially as and for the purpose specified.

4. In a fire extinguisher, the combination of a reservoir for a fire extinguishing liquid having a discharge outlet and an opening 80 therein; a removable cover for said opening having an annular depending flange with internal and external screw threads; a receptacle for a gas generating material having screw threaded connection with the external threads of the cover flange to suspend said receptacle in the reservoir and with which the cover cooperates to provide a closed receptacle; valves in said cover flange opening into and closing out 85 from the reservoir; a second receptacle having screw threaded connection with the internal screw threads of the cover flange to suspend said receptacle in the first receptacle with the bottom at some distance above the bottom of the first receptacle, the bottom of the second receptacle inclining 90 downward from the walls to the center and having openings therein; a fragile receptacle for a gas generating material supported in said second receptacle; and means including a part passing through the cover and operable from the exterior of the reservoir to rupture said fragile receptacle, substantially as and for the purpose specified.
5. In a fire extinguisher, the combination of a reservoir for a fire extinguishing liquid having a discharge outlet and an opening therein; a removable cover for said opening; a receptacle for a gas generating material connected to said cover to suspend 105 said receptacle in the reservoir and having an outlet leading into the reservoir; a fragile receptacle for another gas generating material, said receptacle having an annular contracted and thinned portion adjacent the bottom; means connected to the cover to carry said fragile receptacle suspended in the first receptacle; and means 110

- including a part passing through the cover and operable from the exterior of the reservoir to rupture said fragile receptacle, substantially as and for the purpose specified.
- 5 6. In a fire extinguisher, the combination of a reservoir for a fire extinguishing liquid having a discharge outlet and an opening therein; a removable cover for said opening; a receptacle for a gas generating material suspended in the reservoir and having an outlet leading into the reservoir; a fragile receptacle for another gas generating material; means to support and suspend said fragile receptacle in the first receptacle; means operable from the exterior of the reservoir to rupture said fragile receptacle; and means to filter the generated gas before it is expelled into the reservoir, substantially as and for the purpose specified.
- 10 7. In a fire extinguisher, the combination of a reservoir for a fire extinguishing liquid having a discharge outlet and an opening therein; a removable cover for said opening; a receptacle for a gas generating material connected to the cover to be suspended thereby in the reservoir and having an outlet leading into the reservoir; a fragile receptacle for another gas generating material; means to support and suspend said fragile receptacle from the cover in the first receptacle; a plunger operable from the exterior of the reservoir to rupture said fragile receptacle; and a third material in the support for the fragile receptacle through which the generated gas is passed before it is expelled into the reservoir to render the gas anhydrous, substantially as and for the purpose specified.
- 15 8. In a fire extinguisher, the combination of a reservoir for a fire extinguishing liquid having a discharge outlet and an opening therein; a removable cover for said opening; a receptacle for a gas generating material connected to the cover to be suspended thereby in the reservoir and having an outlet leading into the reservoir; a fragile receptacle for another gas generating material, a tubular carrier for the fragile receptacle connected to the cover to suspend said receptacle in the first receptacle; a plunger having a perforated head of substantially the same diameter as the carrier for the fragile receptacle to engage with and rupture said receptacle; a perforated disk carried by the flange and spaced from the head; and a material confined between said head and disk through which the generated gas passes to render the gas dry before it passes into the reservoir to be utilized as the expelling agent for the liquid therein, substantially as and for the purpose specified.
- 20 9. In a fire extinguisher, the combination of a reservoir for a fire extinguishing liquid having a discharge outlet and an opening therein; a removable cover for said opening; a receptacle for a gas generating material connected to the cover to be suspended thereby in the reservoir and having an outlet leading into the reservoir; a fragile receptacle for another gas generating material; means to support and suspend said fragile receptacle from the cover in the first receptacle; a plunger operable from the exterior of the reservoir to rupture said fragile receptacle; and a second plunger passing through and having threaded connection with the cover and operable from the exterior of the reservoir to cooperate with the first plunger to rupture the fragile receptacle; and a material confined between the head and disk of the first plunger through which the generated gas is passed to render the gas anhydrous or dry before it passes into the reservoir to be utilized as the expelling agent for the liquid therein, substantially as and for the purpose specified.
- 25 10. In a fire extinguisher, the combination of a reservoir for a fire extinguishing liquid having a discharge outlet and an opening therein; a removable cover for said opening; a receptacle for a gas generating material connected to the cover to be suspended thereby in the reservoir and having an outlet leading into the reservoir; a fragile receptacle for another gas generating material, a tubular carrier for the fragile receptacle connected to the cover to suspend said receptacle in the first receptacle; a plunger having a perforated head of substantially the same diameter as the carrier for the fragile receptacle to engage with the fragile receptacle; a perforated disk carried by said plunger spaced from the head; a second plunger passing through and having threaded connection with the cover and operable from the exterior of the reservoir to cooperate with the first plunger to rupture the fragile receptacle; and a material confined between the head and disk of the first plunger through which the generated gas is passed to render the gas anhydrous or dry before it passes into the reservoir to be utilized as the expelling agent for the liquid therein, substantially as and for the purpose specified.
- 30 11. In a fire extinguisher, the combination of a reservoir for a fire extinguishing liquid having a discharge outlet; a receptacle for a gas generating material in said reservoir having an outlet leading into the reservoir; a fragile receptacle for another gas generating material supported in the first receptacle; means operable from the exterior of the reservoir to rupture said fragile receptacle; and means through which the generated gas is passed to render it dry and non-acid before it enters into the reservoir, substantially as and for the purpose specified.
- 35 12. In a fire extinguisher, the combination

of a reservoir for a fire extinguishing liquid having a discharge outlet and an opening therein; a removable cover for said opening; a receptacle for a gas generating material suspended in the reservoir and having an outlet leading into the reservoir; a fragile receptacle for another gas generating material. said receptacle having an annular

contracted and thinned portion adjacent the bottom; means to support said fragile receptacle in the first receptacle; and means including a part passing through the cover and operable from the exterior of the reservoir to rupture said fragile receptacle, substantially as and for the purpose specified.

GEO. T. PEARSONS.
